UNITED STATES PATENT OFFICE.

GUSTAV J. GRUENDLER, OF CLAYTON, MISSOURI.

REFRIGERANT CONTAINER.

Original application filed August 2, 1926, Serial No 126,655. Divided and this application filed November 4, 1927. Serial No. 231,035.

My invention relates to refrigerant containers and more particularly to refrigerant containers such as are adapted to be used to cool show case refrigerators.

This application is a division of my pending application, Serial No. 126,655, filed August 2, 1926, and this invention consists of the improvements set forth below.

Heretofore in refrigerant containers of this type no adequate means for allowing a rising and falling of air up and down through the container has been provided. When the container was filled with a cooling medium such as ice and salt or brine in which a cooling coil was immersed as described in my application Serial No. 126,655 referred to above, since no means for allowing a movement of the air up and down through the container was provided a stagnant body of air collected above the refrigerant container, thereby greatly decreasing the efficiency of the container in cooling the refrigerator.

The principal object of my invention is to provide a refrigerant container in which a vertical and horizontal circulation of air throughout the whole container is allowed.

In the accompanying drawings Figs. 1 and 2 and elevation and plan, respectively, of one embodiment of my invention; Fig. 3 is a section along the lines 3—3 in Fig. 2; Fig. 4 is a section along the lines 4—4 in Fig. 2; and Fig. 5 shows a slightly modified form of my invention.

Referring to the figures, both of the forms of refrigerant container shown therein as embodying my invention are preferably made of metal. In each embodiment the refrigerant container has an upper portion 1 open at the top and a lower portion divided into a plurality of side legs 2 and an intermediate leg 3 all extending downwardly from said upper portion. The form of container shown in Figs. 1, 2, 3 and 4 have the side legs thereof open at the bottom, as shown, and are otherwise adapted and arranged to be filled with cracked ice and salt as a cooling medium. The form of container shown in Fig. 5 has the lower ends of the downwardly extending legs closed and otherwise adapted to be filled with brine with a cooling coil immersed therein, all as shown in my previous application referred to above. These legs are spaced apart to form air passages 4 extending vertically through the refrigerant

container from front to back between adjacent legs, as clearly shown in the figures. The air passages 4 are open along the bottom of the container, have their sides formed by the walls of adjacent legs, and have the upper wall 5 thereof positioned substantially midway the top and bottom of the refrigerant container.

A plurality of air ducts 6 are positioned to lead through the upper portion and, preferably, are arranged with the lower ends thereof opening through the upper wall 5 into an air passage 4 and with the upper ends thereof terminating just below the top of the refrigerant container but above the normal level of brine, ice and salt or other cooling medium in the container which level is indicated by the dotted lines in Figs. 1, 3, 4 and 5. Braces 7 may be provided to extend between adjacent air ducts 6 and between the end air ducts and the side walls of the upper portion 1 to prevent the air ducts from being bent out of position by movement of the brine in the container or, if the refrigerant container is adapted for use with ice and salt, to prevent the air ducts from being moved and bent when ice is introduced into the container.

In the form of invention shown in Figs. 1 to 4, inclusive, the intermediate leg 3 is closed at its lower end and in order that the brine resulting from the melting of the ice in the intermediate leg may flow from the refrigerant container I provide tubes 8 extending between the intermediate leg and the side legs, as shown in the figures. I prefer that only two tubes be provided, one at each end of the container, as shown in Fig. 4. In the embodiment of my invention shown in Fig. 5, the refrigerant container as stated, is adapted to be filled with brine and in this embodiment the tubes 8 will function in the manner described in my previous application, referred to above, and from which this application is divided.

When a refrigerant container embodying my invention is filled with a cooling medium and is positioned in a refrigerator the walls of the refrigerant container will be cooled and the air in the refrigerator and especially the air above the refrigerant container will be cooled and will fall downwardly around the refrigerant container and some of the air above the refrigerant container will pass downwardly through the air ducts 6 into the

air passages 4 during which passage it will be further cooled by the walls of the air ducts and also by the adjacent walls of the downwardly extending legs at either side of the 5 air passages 4.

I prefer that the air ducts 6 be frusto-conical in shape with the large end at the top, as in the embodiment of my invention shown in Figs. 1 to 4, inclusive, since as the air is 10 cooled and falls downwardly it contracts in volume. However, I do not purpose to limit my invention to any shape or form of air ducts and the air ducts may be cylindrical in shape, as in the embodiment shown in Fig. 5.

15 It may be readily seen that the details of construction of various embodiments of my invention may be changed within wide limits without deviating from the spirit of the claims included below.

20 What I claim as new and desire to secure by Letters Patent, is:

1. A refrigerant container for refrigerators having an air passage extending therethrough, an air duct extending downwardly 25 through said container from above said refrigerant into said air passage.

2. A refrigerant container for refrigerators having an air passage extending horizontally therethrough from front to back, a plurality 30 of air ducts extending downwardly from above said refrigerant through said container into said air passage, and said air ducts being frusto-conical in shape with the large ends thereof at the top.

35 3. A refrigerant container for refrigerators comprising an upper portion with a plurality of legs extending downwardly therefrom, said legs being spaced apart to form an

air passage between adjacent legs, air ducts leading through said upper portion of said 40 refrigerant container into said air passage.

4. A refrigerant container for refrigerators comprising an upper portion with a plurality of legs extending downwardly therefrom, said legs being spaced apart to form an 45 air passage extending through said refrigerant container between adjacent legs, and a plurality of air ducts leading through said upper portion of said refrigerant container into said air passage.

5. A refrigerant container for refrigerators comprising an upper portion with a plurality of spaced legs extending downwardly therefrom, said legs being arranged to form one or more air passages extending through 55 said refrigerant container, and a plurality of air ducts extending downwardly through said upper portion of said container into said air passages.

6. A refrigerant container for refrigerators comprising an upper portion with three substantially parallel legs extending downwardly therefrom, said legs being spaced apart to form two air passages extending through said container, a plurality of air 60 ducts extending from near the top of said refrigerant container into said air passages, and tubes connecting the intermediate of said legs with each of the other legs near the bottom thereof, said tubes being arranged and positioned so that brine may flow between said intermediate leg and each of said other legs.

In witness whereof I have signed my name to this specification.

GUSTAV J. GRUENDLER.
